DESIGN FOR A CIGARETTE CONTAINER

Ralph Webber and Charles Horace Webber,
New York, N. Y.

Application November 15, 1944, Serial No. 116,333

Term of patent 14 years

(CL. D85—2)

To all whom it may concern:

Be it known that we, Ralph Webber and Charles H. Webber, citizens of the United States, residing at New York, in the county of New York and State of New York, have invented a new, original, and ornamental Design for a Cigarette Container, of which the following is a specification, reference being had to the accompanying drawing, forming part thereof.

In the drawing:

The front and rear sides of the container are similarly transparent while the rest of the container is opaque and of a contrasting hue.

We claim:

The ornamental design for a cigarette container, as shown and described.

RALPH WEBBER.

CHARLES HORACE WEBBER.
